UNITED STATES PATENT OFFICE.

IVAN ENGSTROM AND JOHN BLOOM, OF CHICAGO, ILLINOIS.

HORSESHOE.

1,075,343.

Specification of Letters Patent.

Patented Oct. 14, 1913.

Application filed September 22, 1911. Serial No. 650,679.

To all whom it may concern:

Be it known that we, IVAN ENGSTROM and JOHN BLOOM, citizens of the United States, and residents of the city of Chicago, in the 5 county of Cook and State of Illinois, have invented certain new and useful Improvements in Horseshoes; and we do hereby declare that the following is a full, clear, and exact description of the same, reference be- 10 ing had to the accompanying drawings, and to the numbers of reference marked thereon, which form a part of this specification.

Many different methods and constructions have been devised for renewing calks 15 on horse shoes without the necessity of removing the shoe from the hoof. These have proven as a rule, unreliable. In some instances, the calk has been threaded into the shoe and when threaded into the shoe is frequently sprung by the stress applied thereto 20 in pulling and if not broken out, attempt to remove the same usually results in breaking the threaded portion in the shoe and making it impossible to renew the calk. In some instances, such constructions also strip the 25 thread. Not only so, the stress exerted upon the calks is not evenly applied and when applied more upon one side than upon the other, it may result in loosening or un- 30 threading the calk in the shoe and in consequence the calks are frequently lost from the shoe and the driver is unaware of the loss until the horse may be shod.

The object of this invention is to so construct and assemble removable calks upon horse shoes as to enable the calks to be readily removed, leaving the horse smooth 35 shod when it is desired, and to be quickly returned to place whenever required and the 40 parts thereof subjected to wear renewed as may be required, thus enabling the calks to be kept sharp.

It is also an object of the invention to afford a construction whereby the various 45 calks are protected from stubbing, or, in other words, the striking of the toe calk upon the pavement as the foot swings forward.

The invention consists in the matters hereinafter described and more fully pointed out and defined in the appended claim.

In the drawings: Figure 1 is a bottom plan view of a horse shoe provided with removable calks embodying our invention. 55 Fig. 2 is a fragmentary view looking in the direction indicated by the arrows 2—2. Fig.

3 is a section taken on line 3—3 of Fig. 1. Fig. 4 is a section taken on line 4—4 of Fig. 1. Fig. 5 is an end elevation of the heel of the shoe and calk. Fig. 6 is a section on line 60 6—6 of Fig. 5. Fig. 7 is a slightly modified construction illustrating the application of our invention to a plate. Fig. 8 is a section on line 8—8 of Fig. 7. Fig. 9 is a longitudinal section of the heel calk. 65

As shown in said drawings: Referring first to the construction shown in Figs. 1 to 6 inclusive, 1, indicates the shoe, which conveniently may be provided with a relatively broad flat toe calk 2, which is recessed on its 70 rear side to afford a seat for the calk block 3. The shoe on its inner side at the bend is also shaped to afford a recess to engage the lip or upwardly directed flange 4, of the calk block 3, as shown in Figs. 1 to 3 inclusive. The calk block is shaped complementally therewith of a thickness approximately corresponding with the thickness of the flat toe calk 2, integral with the shoe so that when the shoe is new and first applied, 80 the same afford a continuous flat surface on the under side the shoe. Said calk block is provided with an aperture therethrough near its middle and front edge and inserted therein and threaded into the shoe is a steel 85 screw. The calk block is provided on each side of the screw aperture with apertures extending therethrough equi-distant from the ends. Said apertures are cylindric and of substantially uniform diameter except on 90 the inner side of the calk block where the same are reamed out, as shown in Fig. 4, to receive the head of the removable calk 6. Said removable calks are preferably constructed with a central core 8, of hardened 95 steel and an outer investment 9, of soft iron so that the natural wear of the calk serves at all times to keep the same sharp.

The heel calk is applied substantially the same as described with reference to the toe 100 calk. In other words, a relatively broad flat heel calk 10, integral with the shoe, is milled to afford a groove or recess 11, on its front side and a corresponding recess 12, on its outer side and fitted thereinto is the heel 105 block 13, which is provided on the inner side with an integral flange 14, to fit within the inner side of the shoe, as shown in Fig. 5. One or more screws 15, are inserted through the heel block and threaded into 110 the shoe to engage the same in place and one or more calks 6, are engaged in the heel

block as before described with reference to the toe calks.

In applying the calks to plates in which it may not be desirable to provide an integral toe or heel calk, the calk block 16, for the toe is constructed of a comparatively thin plate of metal provided with its aperture to receive the calk 17, as shown in Fig. 8, and a recess is provided in the shoe of sufficient depth to receive the head of the calk 17, which thus assists in rigidly engaging the calk block in place. Stops or shoulders 20, integral with the shoe are provided at each side of the toe and heel calks and extend into recesses 21, in said calks to assist the screws in preventing the slipping of the calks.

The calks may, of course, be constructed as before described with reference to the construction shown in Figs. 1 to 6. In a similar manner the heel block 18, is secured upon the shoe by means of the screw 19, and the heel of the shoe is provided with an aperture 20, as shown in Fig. 9, to receive the head of the calk 17, thus holding the heel block from turning. Of course, a sufficient thickness of metal should be provided to protect the hoof against any possible injury from downward pressure on the calk. Any number of screws may be employed in any of said blocks. While we have shown but one in each, it is, of course, to be understood that the number will vary with the necessities of the case.

The operation is as follows: In operation, should it be desired to remove the calks, it

may be done by removing the screws, permitting the calk blocks with the attached calks to fall from the shoe. In this way the horse is, of course, smooth shod. The calks, however, may be very quickly restored by inserting the calks into the calk blocks and screwing the blocks into place on the shoe. Should the calks become worn or injured, they may be quickly renewed. All of the parts are small and comparatively inexpensive and renewal may be effected with a moiety of the expense required to re-shoe a horse.

Of course, we do not purpose limiting this application for patent otherwise than necessitated by the prior art, for many details of the construction and arrangement may be varied without departing from the principles of this invention.

We claim as our invention:

A calk block embracing a flat plate, a lug integral therewith and extending outwardly therefrom, a horse shoe having a recess in the rear edge, an integral recessed toe calk at the forward edge, said calk block adapted to engage within said recess, and removable calks inserted through said calk blocks.

In testimony whereof we have hereunto subscribed our names in the presence of two subscribing witnesses.

IVAN ENGSTROM.
JOHN BLOOM.
